J. F. KELLER

ADJUSTABLE ROOF FOR SILOS

Original Filed April 12, 1921

9.1 19 Inventor
John F. Keller
by D. W. and F. A. Attig

UNITED STATES PATENT OFFICE.

JOHN FREDERICK KELLER, OF VICTOR, IOWA.

ADJUSTABLE ROOF FOR SILOS.

Application filed April 12, 1921, Serial No. 460,749. Renewed October 8, 1923.

To all whom it may concern:

Be it known that I, JOHN F. KELLER, a citizen of the United States, and a resident of Victor, in the county of Iowa and the State of Iowa, have invented a certain new and useful Adjustable Roof for Silos, of which the following is a specification.

This invention relates to improvements in silo roofs. A considerable difficulty has been experienced in the past in filling silos having roofs fastened to the top. While it has been possible to fill them to the top at the time the silage is being placed in the silo, a considerable space is wasted due to the fact that the silage settles six or eight feet after several days' time materially reducing the capacity of the silo.

In filling silos that have no roofs, it is sometimes customary to place a detachable casing on the upper edge of the silo which may consist of woven wire or a slatted fence of about six or eight feet in height and is filled at the time the silo is filled. When the silage settles, it will then just about fill the silo. The casing may then be removed.

It is the object of my invention to provide a roof for a silo which may be adapted to be elevated a considerable distance above the upper edge of the silo so that a circular detachable casing or fence may be placed above the upper edge of the silo, and the silo and the casing filled with silage, after the silage settles, the casing may be removed and the roof lowered into position.

More specifically, it is the object of my invention to provide an improved roof for silos of comparatively simple, durable and inexpensive construction which is adapted to be elevated or lowered relative to the upper edge of the silo.

A still further object is to provide means designed to be detachably secured to the upper edge of the silo for supporting the roof above referred to when in its raised or lowered position.

These and other objects will be apparent to those skilled in the art.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is an end elevation of my im-

proved roof and roof raising device as applied to a silo.

Figure 2 is a side elevation of the same.

Figure 3 is a central, transverse sectional view of my improved roof.

Figure 4 is a detail longitudinal sectional view of the same.

Figure 5 is a side elevation of one of the brackets for securing the roof in position.

Figure 6 is an end elevation of Figure 5.

Figure 7 is a detail sectional view taken on the line 7—7 of Figure 5.

I have used the reference numeral 10 to indicate a silo which may be built of either wood, hollow tile or cement in the usual way. The roof of the silo may be built as a unit and elevated in position as the silo is built, if it is so desired, and comprises beam members 11 which are arranged parallel with each other and spaced apart a distance equal to substantially of about three-fourths the diameter of the silo. These members are secured together by means of transverse pieces 12. Arranged near the central portion of the pieces 12, are parallel members 13 parallel with the members 11 and spaced apart so as to receive a vertical member 14 at each end and between them. This member has its upper end extending upward a slight distance and designed to receive two members 15 which are parallel to the members 13.

These members 15 are braced by means of braces 16, the upper edge of the members 15 being considerably above the upper edge of the members 11, and provided with means for supporting the roof board 17. These roof boards are so formed that they form a circle as viewed from the top to conform with the shape of the silo which is circular, and are of such length as to have their ends overhang the walls of the silo a considerable distance. The pieces 15 and 13 are of such length as to permit the vertical member 14 to project outside of the silo wall, as clearly shown in Figures 1 and 2.

For closing the ends of the roof portion, I have provided circular end pieces 18 which have their ends secured to the outside faces of the members 11 and passed around the ends of the members 13 and 15, as clearly shown in Figures 1 and 2.

By this arrangement, I have formed a roof which is comparatively simple and cheap to build due to the fact that the boards

17 are of uniform width instead of being made tapered as is usually the practice in circular roofs, and the beams 11, 13 and 15 are of stock material and require no fitting 5 with the exception of possibly beveling the beams 11 on the top, which is not absolutely necessary. This at the same time provides a rigid construction whereby the roof may be lifted by the vertical members 14.

10 For adjustably securing the roof in position on the silo, I have provided a bracket designed to be secured to the upper edge of the silo and on the outer face of the wall, at diametrically opposite positions. 15 These brackets are detachable and they may be applied to either the wood or masonry silos, and preferably comprising two parallel straps 19 having inwardly projecting hook portions 20, the said members 19 being 20 secured together by means of cross pieces 21, 22, 23 and 24. The cross piece 21 is provided at one end with a laterally extending portion 25 which is provided with an opening for receiving one end of a rope 26. The 25 opposite end is provided with a projection designed to receive a pulley 27.

This member 21 also has a loop portion 28 at its central portion, as clearly shown in Figure 7, which is of such size as to receive 30 one of the members 14 of the roof and to permit it to slide freely therein. The member 23 is also provided with a loop portion 29 similar to the loop portion 28 and intended for the same purpose. The members 28 and 29 are spaced apart such a distance that one of the members 14 may be 35 slidably mounted therein, and when so mounted the said member may be held against lateral swinging movement.

40 The member 22 which is mounted adjacent to the lower edge of the member 21 and provided at each end with a lateral projection 30. The member 24, which is mounted adjacent to the lower edge of the member 23, is also provided with similar projections 31. These projections 30 and 31 are provided with holes 32.

When it is desired to place the brackets on a silo of masonry construction, the hooks 50 20 are placed over the top edge of the silo at diametrically opposite positions, after which the rods 33 are passed around the silo having their ends entering the openings 32. A nut 34 is placed on each of the ends of the rods which are then tightened and the bracket held securely in position, it being understood, of course, that the rods 33 are 55 of a length substantially of one-half the circumference of the silo so that the two brackets may be rigidly secured in position. If a wood silo is used, the brackets may be bolted in position by passing bolts through the openings 35 in the pieces 19 and into the wall of the silo. This could be done with 60 masonry silos if so desired. After the bracket-

ets have been placed into position, I elevate the roof in position and pass the ends of the members 14 down through the loop portions 28 and 29, or in the case of large silos, I sometimes build a roof on the top 70 of the silo after the silo has been constructed, in which case the brackets are placed with their loop portions 28 and 29 over the members 14 and slid upwardly into position and then fastened. 75

For raising and lowering the roof, I have provided a pulley 36 on the lower end of each of the members 14 through which the rope 26 is passed, and then through the pulley 27, then through a pulley 37 which is secured to the base of the silo. The rope from the opposite side of the silo is brought to a second pulley 37, the two pulleys being arranged in a position substantially midway between the members 14 and at the base of 85 the silo.

For operating the rope, I have provided a jack formed of inclined members 38 which are spaced apart and tied together by means of cross pieces 39, the pieces 38 being arranged with their upper ends adjacent to the side of the silo, while the lower ends rest on the ground some distance from the foundation, as clearly shown in Figures 1 and 2.

These members 38 are designed to have a drum 40 rotatively mounted in position between them. This drum is provided with a crank 41 at each end, and a ratchet member 42, said ratchet being designed to be engaged by a pawl 43. The pulleys 37 are mounted at a point near the bottom of the silo in such a manner that the ropes 26 may be wound upon the drum, as shown in Figures 1 and 2, in such a manner that as the said drum is rotated, the members 38 will be forced against the side of the silo and against the ground so as to firmly hold it into position. The further rotation of the drum will cause the members 14 to be elevated in unison and the roof to be elevated. After the roof has been elevated to a position substantially as shown in the detail Figure 3, the silo is then ready to be 110 filled. 115

After the silo has been filled to the top, a circular wire fencing, or similar device, may be placed on the upper edge of the silo and the said wire portion filled. After the silage has settled, the roof may be then lowered into the position shown in Figure 1. The loop portions 28 and 29 of the brackets serve to hold the roof against swinging movement when it is in its elevated position, and also serves to hold the roof in its proper position 120 when in a lowered position. The roof is held in its upper position by means of the pawl 43 being in engagement with the ratchet 42.

By this arrangement, it will be seen that 125

I have provided a roof which may be economically constructed and which is also adapted to be elevated and lowered relative to the top of the silo for the purpose as 5 before stated.

I claim as my invention:

1. In a device of the class described, a bracket provided with hooks designed to rest on the upper edge of a silo wall and provided with guide ways for slidably mounting vertically moving members, and retaining bands for said brackets designed to surround the silo wall.

2. The combination of a silo, a unitary roof member adapted to be raised and lowered at the upper end of said silo, means for raising and lowering said roof member comprising downwardly projecting members secured to said roof member, a pulley 20 in the lower end of each of said downwardly projecting members, bracket members having hooks for engaging the upper edge of said silo wall and guides for said downwardly extending members, a rope securing lug and pulley and means for securing the bracket against transverse movement relative to the wall, pulleys at the bottom of said silo, a cable for each of said cable lugs designed to pass through the pul-

leys in the lower end of said downwardly extending members, then through the pulleys of said brackets, thence downwardly to the bottom end of said silo and through the pulleys at the bottom of said silo, a drum for simultaneously winding both of said cables and means for locking said drum against unwinding.

3. In a device of the class described, a bracket provided with hooks designed to rest on the upper edge of a silo wall and provided with guide ways for slidably mounting vertically moving members, and retaining bands for said brackets designed to surround the silo wall, said bracket also being provided with a rope retaining lug and a rope pulley.

4. In a device of the class described, a bracket comprising parallel bars each having a hook at its upper end, a transverse bar near said hooks, a pulley in one end of said transverse bar and means for attaching a rope in the other end of said transverse bar, a guide loop in the central portion of said bar, a transverse bar near the lower end of said parallel bars having a guide loop and a set of transverse hook bearing bars.

Des Moines, Iowa, February 19, 1921.
JOHN FREDERICK KELLER.
